(57) **CLAIM**

The ornamental design for a pet feeder as shown and described.

DESCRIPTION

FIG. 1 is a top, front, right perspective view of a pet feeder of my new design;

FIG. 2 is a bottom, rear, left side perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a top, front, right perspective view of the pet feeder, shown in an alternative configuration for clarity of disclosure; and,

FIG. 10 is a top, front, right perspective view of the pet feeder in a condition of use.

In all views, the equal-length broken lines on the pet feeder depict unclaimed portions of the pet feeder, and form no part of the claimed design.

1 Claim, 10 Drawing Sheets
